AUTOMATIC BLEEDER FOR WATER AND OIL
SEPARATION

Richard A. Werts, Wilmington, Calif.

Application January 16, 1948, Serial No. 2,645

3 Claims. (Cl. 210—51)

1

This invention relates to an automatic water bleeder for oil tanks, scrubbers and the like.

An object of the invention is to provide an improved automatic water bleeder which is more stable in its operation to maintain the water level in the tank or similar receptacle below a predetermined level.

With the foregoing and other objects in view, which will be made manifest in the following detailed description and specifically pointed out in the appended claims, reference is had to the accompanying drawings for an illustrative embodiment of the invention, wherein:

The figure is a partial view of a tank illustrating diagrammatically the manner of connecting the automatic water bleeder in accordance with the present invention.

Referring to the accompanying drawings wherein similar reference characters designate similar parts throughout, 10 indicates a tank, scrubber or similar receptacle within which water which has settled out is indicated at W. The oil contents are indicated at O above the water. The water is bled off from the tank through a water outlet pipe 11 and the oil is conducted from the tank through an oil outlet pipe 12. Flow through the water outlet pipe 11 is controlled by a diaphragm valve, the valve housing of which is indicated at 13 and which has a suitable valve closure therein which may conform to any conventional or preferred construction that is operable by means of a stem 14 connected to a diaphragm 15 within a diaphragm housing 16. A connection 17 connects the diaphragm housing with the water outlet pipe 11 so that pressure existing within the water outlet is effective on the under side of the diaphragm 15 to urge the diaphragm valve to open and permit flow of water through the water outlet pipe 11. The weight of the valve, its stem 14 and the diaphragm 15 biases or urges the valve to close and pressure is conducted to the diaphragm housing 16 to be effective on the upper side of the diaphragm to urge the valve to close.

Heretofore customary practice has been to connect a vertical pipe from the top of the diaphragm housing 16 at or about the location of the reference character A and run this pipe upwardly to a location vertically thereabove in the neighborhood of the reference character B. Then to connect this vertical length of pipe into the tank wall at or about the location of the reference character C. This connection C—B—A, on being filled with oil, would conduct pressure to the top of the diaphragm 15 equal to

2

the vertical length of the column A—B plus the column of oil within the tank above the level of the connection C plus any gas pressure head existing in the top of the tank. The pressure that was effective on the under side of the diaphragm 15 was equal to the height of the column of water within the tank above the top of connection 17, plus the weight of the column of oil thereover plus the pressure head, if any, that existed in the top of the tank. The oil being lighter than water would, of course, exert less pressure on top of the diaphragm than the combined oil and water column effective on the under side of the diaphragm. However, the difference was largely balanced by the biasing effect of the weight of the valve closure, its stem 14, and the diaphragm 15, so that as the level of water W rose in the tank the increased pressure created by the increase in water head was effective to open the valve 13 and permit water to be bled from the tank. Conversely, if the water level fell the decrease in water head effective on the under side of the diaphragm permitted the valve to close.

It has been observed, however, that when the diaphragm housing 16 is connected to the tank 10 through piping indicated by the reference characters, A—B—C, in the course of time the water level in the tank would gradually rise until it approached the oil outlet 12 so closely that water would sometimes be carried over with the oil through the oil outlet. When this occurred it became necessary to dismantle the various connections and effect a clean-out after which the bleeder would function properly for a short period of time. Thereafter the water level would again gradually rise toward the oil outlet 12 and a second clean-out would be required.

I have determined that the cause of such failure of the bleeder to continue to function properly is due to the fact that the oil O within the tank contains considerable amounts of dissolved gas and that when the oil in the connections C—B—A is thus isolated, in the course of time, this isolated oil in the piping becomes continually more dense due to the fact that its dissolved gas slowly escapes therefrom and re-enters the tank and passes out with the oil issuing from the oil outlet pipe 12. The increase in density in the oil in the vertical column B—A is effective to increase the pressure on the top of the diaphragm 15 so that with the passage of time as the oil in this column gives up its entrained gas and becomes more and more dense, the pressure that is effective on the diaphragm

urging the valve to close increases and the water level within the tank consequently rises.

In order to overcome this objection I connect the top of the diaphragm housing 16 with a horizontal pipe 18 to the oil outlet pipe 12 in such a manner that the connection with the oil outlet pipe 12 indicated at 19 is substantially or approximately horizontally level with the top of the diaphragm housing 16 and by making a connection in this manner I find that the level of the water W within the tank remains substantially constant. This may be explained substantially as follows: Inasmuch as the oil outlet 12 may be regarded as continually or almost continually conducting oil off from the tank, that oil which is within the outlet pipe and particularly in the column between 19 and 20 will have the same density as the oil within the tank. In other words, if the oil within the tank due to its dissolved or entrained gas is quite light, the oil in the outlet pipe 12 between 19 and 20 will have substantially the same density. That oil which is within the horizontal pipe 18 is, of course, largely isolated and in the course of time this oil may become quite dense by having given up its entrained or dissolved gas. This pipe being horizontal, the increase in density of the oil therein will have little or no effect on the pressure exerted on top of the diaphragm 15. On the contrary this dead oil merely functions as a pressure transmitter between the point 19 and the top of the diaphragm housing. Consequently, as the pressure applied to the top of the diaphragm 15 is always equal to the pressure existing at 19 and the pressure at this point is equal to a column of oil above the point 19 to the top of the oil level in the tank measured in terms of that density of oil that exists within the tank, the operation of the improved automatic water bleeder will remain constant to maintain the water level within the tank constant or substantially so.

It is not essential that all portions of the pipe 18 remain constant. Thus, this pipe between the top of the diaphragm housing and the connection 19 may have a dip or a pigtail therein or may even have a siphon therein. As long as the connection with the oil outlet 12 is approximately level with the top of the diaphragm housing, any increase in the density of oil in the connection between 19 and the diaphragm housing will have no apparent effect on the top of the diaphragm 15.

It will thus be appreciated that by properly connecting the diaphragm housing of the diaphragm valve with the oil outlet 12, as above described, any increase in density in the oil that is isolated in the conduit leading to the diaphragm housing is rendered non-effective on the diaphragm. The improved water bleeder is so designed that if desirable it may be pre-loaded with a desirable liquid of desired density in the pipe 18 and the top of the diaphragm housing.

Various changes may be made in the details of construction without departing from the spirit and scope of the invention as defined by the appended claims.

5 I claim:

1. In combination with a tank adapted to contain oil and separated water having a water outlet and an oil outlet, and a diaphragm valve controlling the water outlet, means for connecting the water and oil outlets respectively to the dia-

phragm valve so that water outlet pressure is effective to urge the valve to open and oil outlet pressure is effective to urge the valve to close, the connecting means between the oil outlet and the valve being characterized by being connected to the oil outlet at approximately the same horizontal level as that of the diaphragm valve so that if there is an opportunity for dead oil to collect therein, the dead oil does not have the increase in its density effective on the diaphragm.

10 2. In connection with a tank adapted to contain oil and separated water having a water outlet and an oil outlet and a diaphragm valve controlling the water outlet, means connecting the water outlet to the diaphragm valve so that pressure in the water outlet is effective on the valve to urge it to open, and means connecting the valve to the oil outlet at a point approximately level with the diaphragm valve whereby pressure in the oil out-

let is effective to urge the valve to close and even though the density of oil in the connecting means may increase, its increase will not be effective on the diaphragm of the valve.

15 3. In combination, a tank adapted to contain oil and separated water, a water outlet leading from the tank, an oil outlet leading from the tank, a valve controlling the water outlet, pressure-responsive means subjected to pressure in the water outlet urging the valve to open, said

20 pressure-responsive means being connected by a conduit to the oil outlet so as to be subjected to pressure in the oil outlet urging the valve to close, the conduit connecting the pressure-responsive means with the oil outlet being disposed approxi-
25 mately level with the pressure-responsive means whereby any increase in density in the oil be-
30 tween the oil outlet and the pressure-responsive means will not be effective to urge the valve to close to any materially increased extent.
